Patented Sept. 1, 1925.

UNITED STATES PATENT OFFICE.

CHARLES J. KIRK, OF NEW CASTLE, PENNSYLVANIA.

APPARATUS FOR SHERARDIZING METAL ARTICLES.

Application filed December 20, 1921. Serial No. 523,667.

To all whom it may concern:

Be it known that I, CHARLES J. KIRK, a citizen of the United States, and resident of New Castle, in the county of Lawrence and State of Pennsylvania, have invented a new and useful Improvement in Apparatus for Sherardizing Metal Articles; and I do hereby declare the following to be a full, clear, and exact description thereof.

10 My invention relates to the art of sherardizing pipe couplings, castings, nails, wire and other metal articles.

One object of my invention is to provide improved sherardizing apparatus whereby the articles to be sherardized are progressively heated during the sherardizing treatment with zinc dust.

Another and more specific object of my invention is to provide sherardizing apparatus including a compensating tunnel kiln and a series of rotatable containers, for carrying the articles, together with suitable quantities of zinc dust, through the tunnels of the kiln in opposite directions and preferably by gravity.

A further object of my invention is to provide an improved sherardizing drum so constructed as to roll on tracks such as are ordinarily provided in tunnel kilns.

30 In the ordinary method of sherardizing metal articles, the articles to be treated are placed in a tumbling drum along with a suitable quantity of zinc dust containing some zinc oxid. The drum is then heated to the temperature necessary to cause the metal articles within the drum to absorb a surface coating of zinc, and the drum is rotated to tumble the articles and the zinc together and to bring all parts of the articles into intimate contact with the zinc. It is difficult to control the temperature within the drum, and it is particularly difficult to raise and lower the temperature of the metal articles slowly, which is desirable because the metal 45 may be injured by too rapid heating and cooling.

According to my present invention, I carry out the sherardizing operation in a drum which is caused to pass through a tunnel kiln, preferably of the compensating or heat-interchanging type, and I thereby heat the articles in a progressive and relatively gradual manner while they are being continuously tumbled into contact with the usual kind and quantity of zinc powder.

The drums in which the articles are sherardized are preferably circular, and may be so arranged as to roll by gravity on tracks extending through the tunnel kiln.

In the accompanying drawing, which shows apparatus suitable for carrying out the method of my present invention, Fig. 1 is a horizontal sectional view through a tunnel kiln containing two series of sherardizing drums; Fig. 2 is a vertical sectional view taken substantially on the line 2—2, Fig. 3; Fig. 3 is a transverse vertical sectional view taken substantially on the line 3—3, Fig. 1; Fig. 4 is an end elevational view showing two connected sherardizing drums; Fig. 5 is a side view, with parts in longitudinal section, of one of the drums of Figs. 1 to 4; Fig. 6 is a cross section through one of the drums, the section being taken substantially on the line 6—6, Fig. 5; and Fig. 7 is an enlarged side view of one of the couplings which connect the drums.

In the drawing the numerals 2 and 3 indicate, respectively, the two passageways or tunnels of a compensating continuous tunnel kiln of well known construction. The tunnels are covered by an arch 4 and are separated by a wall 5 having a row of openings 6 formed near its top, and another row of openings 7 formed near its bottom. Heat is applied from two batteries of furnaces 8 and 9 located on opposite sides of the kiln and communicating respectively with flues 10 and 11. Tracks 12 and 13 are provided in the tunnels 2 and 3 respectively, and the ends of the tunnels are closed by sliding doors 14. These tracks are given a slight inclination from end to end, in order to cause the treating drums to roll through the kiln by gravity. Each track may have a grade of approximately 3° and the tracks are inclined in opposite directions so that the drums will roll by gravity in opposite directions in the two tunnels. Vestibules 15 are provided at both ends of the kiln for admitting the material to be treated without exposing the interior of the kiln to the outer air.

The parts thus far described are of well known construction. A compensating kiln of this kind is commonly operated by introducing cars into the tunnels from opposite ends carrying the porcelain, earthenware or other material to be fired. For example, the cars may be introduced into

the tunnel 2 from the right of Fig. 1, and into the tunnel 3 from the left of Fig. 1. At the entering end, each tunnel is heated only by heat from the adjacent tunnel and the heat in each tunnel becomes progressively greater as the cars advance and may be controlled to heat the articles to any desired temperature and at any desired rate.

The drums 19 in which the articles to be sherardized are carried through the tunnels 2 and 3 consist of circular end plates 20, which are constructed, like railway car wheels, with flanges 21 which run upon the tracks 12 and 13. The end plates 20 are also provided with inner flanges 22 to which a circular sheet-metal shell 23 is secured by rivets 24 or by other suitable means. An opening for loading and unloading the drum is provided at 25 and is closed by a door 26 which fits between flanges 27 formed around the opening 25 and is attached thereto by means of pins 28 and pivoted keys 29 which enter slots 30 formed in the flanges 27 and in the cover 26. Pins 31 are driven through the pins 28 and the keys 29 to hold the door in place.

Hubs 35 are formed at the center of each of the end plates 20 and are provided with grooves 36 to receive couplers 37 which are provided with recesses 38 near their ends. These recesses 38 fit in the grooves 36, which are wide enough to receive two of the couplers as shown in Figs. 1, 2 and 4.

In the operation of the apparatus described above, the pipe couplings, castings or other metal articles to be sherardized are placed in the drums 19 together with a suitable quantity of zinc dust, and the drums are introduced one at a time into opposite ends of the tunnel kiln, the drums entering the tunnel 3 from the right of Fig. 1, as shown by the arrow on this figure, and entering the tunnel 2 from the left of Fig. 1. Each drum is connected by the couplings 37 to the preceding drum, in order that the drums may not rub against each other as they roll through the kiln. While advancing through the kiln, the rolling movement of the drums causes the metal articles to be thoroughly tumbled with the zinc dust. At the same time the interior of each drum is heated progressively and controllably, which assists in the proper coating of the metal and also gives the metal a desirable heat treatment. At suitable intervals one of the drums is withdrawn from the outlet end of each tunnel and the contents removed, and a fresh drum charged with metal articles and zinc dust is introduced into the entering end of the tunnel.

My invention comprises broadly the provision of apparatus for progressively heating sherardizing containers, and particularly in the use of a tunnel kiln for this pur-

pose. A tunnel kiln of the compensating type is preferred on account of its advantages as to economy and regulation of the heat. However, it will be understood that this apparatus may be varied in many respects without departing from the broad features of my invention.

It will also be understood that when a tunnel kiln is employed for sherardizing, the containers in which the articles are carried through the kiln need not be of the specific form herein described, since the drums may be constructed in various other ways within the scope of the appended claims.

I claim as my invention:

1. Sherardizing apparatus comprising a plurality of closed containers and means for advancing the said containers successively and by gravity through a progressively heated chamber.

2. Sherardizing apparatus comprising a compensating tunnel kiln, a plurality of closed rotary containers, and means for advancing the said containers in spaced relation through the said kiln in parallel rows and from opposite ends of the said kiln.

3. Sherardizing apparatus comprising a compensating tunnel kiln, parallel tracks within the said kiln, the said tracks being inclined in opposite directions, and a plurality of closed containers adapted to advance by gravity on the said tracks.

4. Sherardizing apparatus comprising a compensating tunnel kiln containing two tracks inclined in opposite directions, and a plurality of circular sherardizing drums adapted to roll by gravity on said tracks.

5. Sherardizing apparatus comprising a compensating tunnel kiln containing two tracks inclined in opposite directions, a plurality of circular sherardizing drums adapted to roll by gravity on the said tracks, and means for spacing the said drums apart.

6. Sherardizing apparatus comprising a compensating tunnel kiln containing two tracks inclined in opposite directions, a plurality of circular sherardizing drums adapted to roll by gravity on the said tracks, and means for spacing the said drums apart, the said spacing means comprising grooved hubs carried by the said drums and couplers having recesses formed in their ends and adapted to fit in the said grooves.

7. A sherardizing drum comprising flanged circular end plates adapted to roll on railway tracks, and a shell connecting the said end plates, the said shell being provided with an opening closed by a removable door.

8. A sherardizing drum comprising circular flanges end plates adapted to roll on railway tracks and a circular sheet metal shell secured to the said end plates and forming therewith a closed container, the said shell being provided with an opening closed by a removable door.

9. A sherardizing drum comprising flanged circular end plates adapted to roll on railway tracks, a circular sheet metal shell connecting the said end plates and forming therewith a closed container, the said shell being provided with an opening

ried by the said end plates, the said hubs being provided with a circular groove for receiving couplers.

10

In testimony whereof I, the said CHARLES J. KIRK, have hereunto set my hand.

CHARLES J. KIRK.
